(57) **CLAIM**

I claim the ornamental design for bottle cap, as shown and described.

DESCRIPTION

FIG. 1 is a front perspective view of bottle cap incorporating my new design;
FIG. 2 is a rear perspective view thereof;
FIG. 3 is a front elevation view thereof;
FIG. 4 is a rear elevation view thereof;
FIG. 5 is a right-side elevation view thereof, the left side being a mirror image; and,
FIG. 6 is a top elevation view thereof.
